UNITED STATES PATENT OFFICE

2,258,495

LIQUID DISPENSING APPARATUS

Robert J. Jauch, Fort Wayne, Ind., and Howard Somervell, Evanston, Ill., assignors to The Wayne Pump Company, Fort Wayne, Ind., a corporation of Maryland

Application April 6, 1938, Serial No. 200,292

2 Claims. (Cl. 103—113)

This invention pertains to liquid dispensing apparatus and pumping means to be used in connection therewith, or in connection with installations for dispensing liquid as in filling stations, or in connection with installations dispensing large quantities of liquid rapidly and efficiently as in bulk station installations, city pumping stations, and the like.

It is an object of this invention to provide a liquid dispensing apparatus wherein entrained air is separated from the liquid to be dispensed before the apparatus is operable to dispense clear liquid.

Another object is to provide a liquid dispensing apparatus wherein liquid is dispensed only after a predetermined pressure is built up.

Still another object is to provide a liquid dispensing apparatus so constructed and arranged that entrained air is separated on the suction side of the pump.

Yet another object is to provide a liquid dispensing apparatus which is self-priming.

A further object is to provide a liquid dispensing apparatus wherein the removal of entrained air is effected through the use of an ejector.

A still further object is to provide a liquid dispensing apparatus wherein entrained air is eliminated through use of an ejector where the ejector may be controlled after air elimination.

With these and various other objects in view, the invention may consist of certain novel features of construction and operation as will be more fully described and particularly pointed out in the specification, drawing and claims appended hereto.

In the drawing, which illustrates embodiments of the device and wherein like reference characters are used to designate like parts—

Figure 1 is a fragmentary elevation, more or less diagrammatic, showing a portion of the liquid dispensing apparatus embodying the invention;

Figure 2 is an elevation corresponding to Figure 1 showing another modified form of the invention;

Referring to the forms of construction illustrated herein, it is of course to be understood that in these forms wherein the pump assembly is used in a liquid dispensing apparatus, said apparatus is adapted to be provided with a suitable casing such as illustrated in application Serial No. 2,282, filed January 17, 1935, and a meter similar to that illustrated in application Serial No. 85,426, filed June 15, 1936, may be used to drive registering mechanism such as shown in Patent

No. 2,111,996, granted March 22, 1938. In the constructions illustrated herein, where they are used in a liquid dispensing apparatus, it is of course understood that the pump 22 is adapted to be connected to a suitable source of supply (not shown) through the suction tube 20, and in general the outlet side of the pump is connected through air separating means to the meter which drives indicating mechanism, the outlet side of the meter being connected through a suitable sight gauge to the usual dispensing hose and nozzle assembly.

Referring first of all to the modification illustrated in Figure 1, the outlet side of the pump 22 is connected to one end of the conduit 142, the other end of which is connected to the inlet 144 of the air separator 146. In general the pump shown is a self-priming, positive displacement rotary pump including a casing having the impeller 24 driven by the usual motor (not shown) through the pulley 26. The casing is provided with the suction chamber 28 and the pressure or outlet chamber 30. The bypass chamber 32 is connected to the suction chamber 28, and the spring-pressed valve 34 is adapted to permit bypass of liquid from the pressure chamber to the suction chamber when a predetermined pressure is built up in the pump. The separator 146 is provided with the chamber 148 provided with said inlet and with an outlet 150 separated by means of the baffle 152. The air separator is also provided with the jet chamber 154 connected to the chamber 148 through the Venturi jet 156, the inlet or larger opening being from the chamber 148. The jet is aligned with a Venturi tube 158, said jet and tube forming an ejector communicating with the upper dome 160 of the float or atmosphere chamber 162, the dome 160 being preferably provided with baffles 164 disposed between the ejector and the vent tube 166 extending upwardly and, in the case of a pump, preferably to the upper portion of the casing thereof. The float 168 is disposed within said float chamber, being provided with the guide 170 in cooperative engagement with the stationary guide member 172 provided in said chamber, and said float is pivotally connected as at 174 to the lever 176, the other end of said lever being pivotally connected as at 178 to the bracket 180 provided in the chamber 162.

A valve rod 182 is pivotally connected as at 184 to the lever 176 intermediate the ends thereof, and is provided with the valve 186 controlling the passage 188, said passage being connected to the conduit 190 connected to the inlet

side of the pump. A conduit 192 is connected as at 194 to the jet chamber 154, the other end of said conduit being connected as through the one-way valve 186 to the pump. The conduit 192 may be provided with the connection or restricted conduit 278 connected as at 282 to the outlet side of the pump adjacent a high point thereof. The outlet 150 of the air separator is connected to the conduit 198 provided with the differential valve 200, said differential valve being connected through the conduit 202 to the inlet side of the meter 204, the outlet side of the meter being connected through the conduit 208 to suitable dispensing means such as the hose and nozzle assembly referred to. The meter shaft 208 is adapted to rotate in accordance with liquid passing through the meter, and operates registering mechanism or computing mechanism as described in said Patent No. 2,111,996. The differential valve 200 is provided with the valve member 210—212 having a spring 214 disposed normally urging said valve toward closed position. Below the valve member the conduit 216 is connected, the other end of said conduit being connected to the inlet side of the pump.

In operation of this form of the device, operation of the pump causes the liquid and vapor to be supplied to the chamber 148 through the conduit 142. The valve 200 being closed, the liquid and vapor will pass through the jet and ejector tube into the dome 160 whence the liquid will be precipitated into the chamber 162 and the vapor will pass through the vent 166. Passage of liquid through the jet and ejector tube will cause a vacuum in the chamber 154 whereby suction will be caused in the conduit 192 removing the vapor from the pump. This vacuum also exhausts vapor from the pump outlet through the restricted conduit 278, but little or no liquid is supplied to the ejector due to the disposition of conduit 278 and the fact it is of smaller size than the conduit 192. The one-way valve of course prevents the suction of the pump when by-passing solid liquid from reversing flow in the conduit 274 or tending to destroy the action of the ejector. After the liquid has reached a certain level in the chamber 162 the valve 186 will be opened by the float 188 and the liquid will be returned through the conduit 190 to the inlet side of the pump. When the pump is pumping solid liquid, the vacuum created below the piston 212 of the differential valve, together with the pressure of solid liquid from the air separator, will cause the differential valve to open whereby the liquid may be measured and dispensed.

In the construction illustrated in Figure 2, the inlet side of the pump is connected through the manifold 21 to the inlet pipe 20, said manifold serving to maintain a predetermined amount of liquid in the pump casing, it being understood that said manifold or an equivalent thereof may be used with all modifications shown herein. The outlet side of the pump 22 is connected to the conduit 218, which in turn is connected to the jet 220 provided in the jet chamber 222, the jet chamber being connected as at 224 to the conduit 226, which in turn is connected to the pump 22 preferably to a high point in said pump as through the one-way valve 228. Disposed in the jet chamber and aligned with said jet there is provided an ejector tube 230 forming an ejector with said jet, connected to the conduit 232 which in turn is connected to the inlet 234 of the chamber 236 of the air separator 238. The chamber 236 is provided with the outlet 240 separated from the inlet 75

by means of the baffle 242 and the upper portion of the chamber 236 is provided with the restricted orifice 244 communicating with the dome 246 of the float chamber 248, the dome being preferably provided with baffles 250 disposed between the orifice 244 and the vent 252. The float 254 is disposed in the float chamber as before, being guided by the member 256 and the stationary member 258.

10 The float 254 is operatively connected to the outer end of the lever 260 as at 262, the inner end of said lever being pivoted to the bracket 264. The lever is connected to the valve rod 266 provided with the valve 268 controlling the discharge 15 270 which is connected to the conduit 272, the other end of said conduit being connected to the inlet side of said pump. The outlet 240 of the air separator is connected to the conduit 198, the differential valve 200, the meter 204 and the outlet 208, the meter being provided with the meter shaft 208. The differential valve is connected to the conduit 216, which in turn is connected to the inlet side of the pump as described in the construction illustrated in Figure 1.

25 In the operation of this form of the device, liquid and vapor in being discharged from the pump passes upwardly through the jet and ejector tube, causing a vacuum to be formed in the jet chamber, whereupon a suction will be caused in the conduit 226 to remove the vapor from the pump 22. The liquid and vapor passing into the chamber 236 causes the vapor to be released through the orifice and the vent 252. The liquid precipitated in the float chamber is returned 30 through the conduit 272 when the valve 268 is opened by the float 254 permitting liquid return to the inlet side of the pump. After the predetermined pressure has been built up, the differential valve 200 will open, permitting supply of 35 liquid to the meter and dispensing means.

40 Although a differential valve is illustrated in the various constructions, it is of course understood that a spring pressed poppet valve may be used in place of the valve 200, in which case the spring is set so that the valve will only open 45 when the pump is pumping solid liquid.

46 It is to be understood that we do not wish to be limited by the exact embodiments of the device shown, which are merely by way of illustration 50 and not limitation, as various and other forms of the device will of course be apparent to those skilled in the art without departing from the spirit of the invention or the scope of the claims.

What is claimed is:

55 1. In a device of the character described, the combination of a pump, the suction side of which is adapted to be connected to a source of liquid supply, an air separator having an inlet and an outlet, a connection between the inlet of said separator and the outlet of said pump, the outlet 60 for liquid from said separator being adapted to be connected to a meter, said separator having a plurality of chambers, one of said chambers having said inlet and outlet, another of said chambers having a restricted vent to the atmosphere and an overflow outlet, said overflow outlet being connected to the suction side of said pump, said separator having a jet chamber interposed between said first named chambers, a jet connecting said jet chamber and said first named chamber, an ejector tube connecting said jet chamber and said second named chamber, and connecting means between said jet chamber and the inlet and outlet sides of said pump.

70 2. In a device of the character described, the

combination of a pump, the suction side of which is adapted to be connected to a source of liquid supply, an air separator having an inlet and an outlet, a connection between the inlet of said separator and the outlet of said pump, the outlet for liquid from said separator being adapted to be connected to a meter, said separator having a plurality of chambers, one of said chambers having said inlet and outlet, another of said chambers having a restricted vent to the atmosphere and an overflow outlet, said overflow outlet being connected to the suction side of said pump, said separator having a jet chamber inter-

posed between said first named chambers, a jet connecting said jet chamber and said first named chamber, an ejector tube connecting said jet chamber and said second named chamber, and connecting means between said jet chamber and the inlet side of the pump whereby liquid passing through said jet and ejector tube causes a vacuum condition in said jet chamber to remove vapor from said pump through said last named connecting means.
